DESCRIPTION

U.S. PATENT DOCUMENTS

FIG. 1 is a perspective view of a asymmetrical carton with
smile edge crease embodying our new design;

2,119,382 A * 5/1938 Cooper 229/164
D208,272 S * 8/1967 Corella D9/416
3,610,514 A 10/1971 Samsing
D244,993 S 7/1977 Drysdale
4,126,266 A * 11/1978 Roccaforte 229/164
4,313,556 A 2/1982 Boyle et al.
D268,328 S * 3/1983 Lovett, Jr. D9/432
4,483,464 A 11/1984 Nomura
4,728,002 A * 3/1988 Ybanez D9/518
4,846,396 A 7/1989 Palazzolo
4,964,562 A 10/1990 Gordon
D347,169 S * 5/1994 Bezerides et al. D9/414

FIG. 2 is a front view thereof;

FIG. 3 is a rear view thereof;

FIG. 4 is a left side view thereof;

FIG. 5 is a right side view thereof; and,

FIG. 6 is a top view thereof.

The carton being shown with a closure cap in phantom lines
that forms no part of the claimed design, and the bottom
forming no part of the claimed design.
